United States Patent Office.

FRANCIS L. KING, OF WORCESTER, MASSACHUSETTS.

Letters Patent No. 65,916, dated June 18, 1867.

IMPROVED EGG-CUTTER.

The Schedule referred to in these Letters Patent and making part of the same.

TO ALL WHOM IT MAY CONCERN:

Be it known that I, FRANCIS L. KING, of the city and county of Worcester, and Commonwealth of Massachusetts, have invented a new and useful instrument or machine called the "Egg-Cutter;" and I do hereby declare that the following is a full, clear, and exact description of the construction of the same, reference being had to the drawings annexed, which make a part of this specification, and which is a perspective view of the same.

Figure 1 shows the machine complete, placed in a vessel ready for use.

Figure 2 shows the cutter-shafts and cutters.

Figure 3 shows a top view of the same.

The framework *a a a a a* sets in the vessel, and supports and holds in position the gearing and cutter-shafts. The cutter-shafts *B B* are properly secured in the frame. At the top the gears *C C* are attached, which connect with the gear *D*. The side gear *E* with crank connects with the gear *D*, and furnishes the propelling power. The cutters *F F* are made of any thin, flat pieces of metal, so as to afford the least possible resistance when in motion, and are securely soldered into slots sawed into the shafts *B B*. The cutter-shafts, as shown in fig. 2, are set near together, and in such a manner that when in motion the cutters pass between each other. The two currents (if any were created) would be antagonistic, and both of equal power; the egg must therefore remain almost motionless while the cutters pass through, and the egg is cut into a fluid ready for use almost instantly.

The motion and operation of the machine will be readily understood by comparing figs. 1, 2, and 3 in the drawing. One or two more cutter-shafts might be added to work within each other substantially as those herein described.

What I claim as my invention, and desire to secure by Letters Patent, is—

The combination of two or more cutter-shafts *B*, having cutters *E* attached, with the gearing *C D E*, arranged and operating essentially as set forth.
